RADIATOR CLEANER

Filed April 22, 1930

Inventor:-

Lloyd J. Trowbridge

by his Attorneys
Howson & Howson.

UNITED STATES PATENT OFFICE

LLOYD J. TROWBRIDGE, OF CAMDEN, NEW JERSEY

RADIATOR CLEANER

Application filed April 22, 1930. Serial No. 446,314.

This invention relates to radiator cleaners and has for an important object thereof the provision of a radiator cleaner of such character that the cleaning may be done under conditions wherein the radiator is expanded so that the channels and passages thereof are of the greatest possible size and the dirt adhering to the walls of these channels has a natural tendency to release therefrom.

10 A further object of the invention is the production of a device of this character permitting circulation through the radiator while heated, and accordingly expanded, of a cleansing fluid which has been atomized.

15 A further object of the invention is the production of an apparatus of this character permitting the cleansing fluid to be delivered through the radiator under considerable force so that small particles of dirt and

20 sediment which would otherwise tend to adhere to the walls of the tubes may be rapidly and efficiently removed therefrom.

25 These and other objects I attain by the construction shown in the accompanying drawing wherein, for the purpose of illustration, I have shown a preferred embodiment of my invention and wherein:

The figure is a diagrammatic view of radiator cleaning apparatus.

30 Referring now more particularly to the drawing, the numeral 10 generally designates an open-topped vat for the reception of the radiator R which is to be cleaned. This vat has arranged therebelow a closed tank 11 for the reception of a liquid cleaning substance of any desired character. Between the bottom of the vat 10 and the top of the tank 11 a connection 12 is provided having a valve 13 arranged therein. Tank 11 is heated

35 through any suitable medium such as a gas heater 14 and has extended thereinto an outlet pipe 15 which opens into the tank at a point adjacent the bottom thereof and has arranged therein a valve 16. The upper end 40 of outlet pipe 15 has an extension projecting adjacent the top of vat 10 and provided with a flexible hose terminus 17 adapted for connection with an inlet pipe 18 of the radiator R. Likewise opening into tank 11 is a pipe

45 19 which is in communication with a suitable

source of air under pressure and has arranged therein a valve 20. Pipe 19 beyond valve 20 from tank 11 has a branch 21 provided with a valve 22 and having its terminus extended into pipe 19 and directed toward the outlet end thereof to provide an ejector 23 for the contents of tank 11.

55 Vat 10 has associated therewith a heating coil 24 of any approved type, this coil having its inlet 25 communicating with the bottom of the vat and its outlet 26 communicating with the vat through the side wall thereof and at a point above the upper surface of a radiator disposed upon the bottom of the vat. Coil 24, as illustrated, may be interposed between 60 heater 14 and tank 11 so that the single heater serves both to heat the tank 11 and this coil.

65 In use of the apparatus the radiator to be cleaned is placed in the vat 10 and connected 70 with the outlet pipe 15 through the flexible hose 17. The contents of tank 11 are heated as are the contents of vat 10 which should be of sufficient depth to submerge the radiator.

75 Valve 16 may then be opened and fluid from the tank 11 will be forced through the radiator by pressure generated in tank 11 through

heating of the contents thereof with the tank closed acting upon sediment therein and tending to loosen the same. This sediment 80 is further loosened by reason of the fact that the contents of vat 10 are heated and kept in constant circulation and, accordingly, tend to thoroughly heat the radiator and cause an increase in dimensions therein 85 which materially assists in removal of caked sediment. Air pressure can then be applied to tank 11 through valve 20 and, if desired, valve 22 may be opened so that the contents

90 of tank 11 which are passing to the radiator will be intermingled with air from the pressure source and will, accordingly, move at a relatively high speed through the radiator R.

95 When air admitted through valve 22 is intermingled with the fluid from tank 11, the fluid is atomized before delivery to the radiator.

When the cleaning operation is completed, the valve 13 may be opened to permit return of a portion of the contents of vat 10 to the 100

5 tank 11. The air inlet pipe 19 to tank 11 having its end disposed adjacent the bottom of the tank will tend to prevent collection of sediment on the bottom of the tank which would otherwise impair the efficiency thereof.

10 Since the construction herein illustrated is obviously capable of a certain range of change and modification without in any manner departing from the spirit of my invention, I do not wish to be understood as limiting myself thereto except as hereinafter claimed.

I claim:

15 1. Apparatus for cleaning automobile radiators and the like, comprising a vat to receive the radiator, means for maintaining a circulation of heated fluid within the vat and about the radiator, a tank for heated cleaning fluid and a conduit for conducting fluid from said tank into a radiator disposed within the vat.

20 2. Apparatus for cleaning automobile radiators and the like, comprising a vat to receive the radiator, means for maintaining a circulation of heated fluid within the vat and about the radiator, a tank for heated cleaning fluid, a conduit for conducting fluid from said tank into a radiator disposed within the vat and means for ejecting the liquid in the tank through said conduit.

25 3. Apparatus for cleaning automobile radiators and the like, comprising a vat to receive the radiator, means for maintaining a circulation of heated fluid within the vat and about the radiator, a tank for heated cleaning fluid, a conduit for conducting fluid from said tank into a radiator disposed within the vat, a source of fluid under pressure communicating with the cleaning tank and means for introducing fluid from the source into the conduit whereby said fluid is atomized.
